UNITED STATES PATENT OFFICE.

WILLIAM W. DEAN, OF ELYRIA, OHIO; CURTIS B. CAMP, TRUSTEE, APPOINTED BY COURT.

HARMONIC SIGNALING DEVICE FOR TELEPHONE SYSTEMS.

1,125,495.

Specification of Letters Patent.

Patented Jan. 19, 1915.

Application filed September 9, 1905. Serial No. 277,688.

To all whom it may concern:

Be it known that I, WILLIAM W. DEAN, a citizen of the United States, residing at Elyria, in the county of Lorain and State 5 of Ohio, have invented certain new and useful Improvements in Harmonic Signaling Devices for Telephone Systems, of which the following is a specification, reference being had therein to the accompanying drawing.

My invention relates to harmonic signaling systems, and particularly to the signal receiving devices used therein.

Specifically stated, it comprises a polarized ringer having a spring mounted armature which with its connected parts is so arranged that the three factors of length, mass and tension may be readily predetermined to secure absolute tuning of each ringer. The armature is carried in a flat yoke secured upon the pole pieces of the ringer magnet, and is pivoted upon pointed screws or studs, being tensioned thereagainst by means of a parallel spring screwed or 20 riveted at its ends to the yoke, and also screwed or riveted at an intermediate point to the armature.

My invention is illustrated in the accompanying drawings wherein:

Figure 1 is a top plan view of a ringer embodying my improvements; Fig. 2 is a side view of the same; Fig. 3 is a detail of the armature pivots.

Referring to the drawings, A indicates a pair of electro-magnet spools mounted upon cores a^o carried and magnetically connected by and through the iron yoke Y. This yoke also carries the permanent magnet M for polarizing the cores and armature, and the adjustable gong posts g, carrying the gongs G. A nice and accurate adjustment of the gongs being required, I mount each gong post upon a segment g^o , pivoted at one end and having teeth at the other which mesh with the threads of a worm g' on a spindle journaled in the drop ears y of the yoke Y.

While all the features I have thus mentioned are of my own design, I do not claim them herein, since they are described and 50 claimed in other co-pending applications. The present invention concerns itself particularly with the armature connections and mounting. The armature itself is shown at A', and carries the clapper-rod a and the clapper a' which is normally positioned intermediate of the two gongs G. The arma-

ture is pivoted upon the yoke B carried by the cores a^o , whereon it is adjustably secured by the nuts a^3 . The nuts may be threaded directly on the cores, or upon the sleeve surrounding the same. The ends of the yoke B are bent down and return at b, and to them are secured by screws or rivets the ends of a stiff spring a^2 , which is also secured by screws or rivets at its middle portion to the armature A'. The tension of this spring determines the tension on the armature and the degree of stiffness in its movement. Other things being equal, the stiffer the spring the higher the rate of vibration of the connected parts. While the armature is thus in a sense carried by a spring, I have found it necessary to determine accurately the line or axis upon which it will swing, and this more particularly because of the length of the spring a^2 . The preferred form of pivot connections is best shown in Figs. 2 and 3, the former being a side view, and the latter a section. The yoke B carries a pair of pointed screws b' , 80 which are tapped down through its body on a transverse line midway between its ends, and secured when adjusted by means of lock nuts b^2 . The armature is provided with openings a^4 to receive the ends of these 85 screws, their points resting upon the upper surface of the steel spring a^2 . The tension of the spring is such as to force the armature up toward the pole pieces of the magnet, and the spring therefore impinges upon the 90 points of the screws with considerable force. As the armature vibrates it turns upon the axis which passes through the points of the two screws, and since this axis lies in the upper plane of the spring itself, I secure a 95 very nice and accurate adjustment for all purposes.

The operation of my invention is sufficiently apparent from the foregoing description. Ordinary ringing currents have 100 no effect upon the armature, but when current of the proper frequency is thrown upon the line, the clapper-rod will be vibrated, the motion building up very rapidly until a loud and sonorous ringing of the gongs is 105 secured. It should be particularly observed that the period of vibration of the clapper-rod and its connecting parts is determined, as well as the frequency of the current to which it will respond, independently of any 110 reactive effect due to the strokes on the gongs. I find that with the parts properly

proportioned, and particularly by giving a slight clearance between the clapper in its extreme position and the side of the gong, the clapper rod will spring at the end of each stroke as the armature strikes the pole piece, and the duration of impact will thus be so short as to render the gong effect negligible, even if it were not already so by reason of the strength of operation.

10 Having thus described my invention what I claim and desire to secure by Letters Patent is:

1. In a harmonic selective ringer, a frame carrying an electro-magnet, a polarizing magnet therefor, a yoke extending across the poles of said magnet and having its ends returned away from the same, a prismatic spring secured by its ends across the ends of the yoke, an armature secured within the 15 yoke and across the poles of the magnet, and upon the middle portion of the spring, substantially as described.

2. In a selective ringer for harmonic signaling systems, the combination of the following instrumentalities: a frame carrying a pair of cores with energizing windings thereon, a pair of gongs adjustably mounted on the frame, an elongated yoke extending across the cores or pole pieces and having 20 projecting ends bent away from the same, a flat spring extending parallel to said yoke and having its ends secured to the ends thereof, an armature secured upon said spring and lying parallel thereto between the same and the yoke with its extremities 25 in juxtaposition to the pole pieces, and a

pivotal support for said armatures, substantially as described.

3. In a ringer, an electromagnet, a gong, an armature clapper rod and clapper rigidly 40 associated, a spring for supporting and pivoting such armature in operative relation to such electromagnet, such spring adapted to be flexed when such armature is acted upon by such electromagnet, and 45 means for maintaining the center of oscillation of such armature in the same position relatively to such electromagnet during the energization thereof.

4. In a ringer, an electromagnet, a pair 50 of gongs, an armature clapper rod and clapper rigidly associated, a spring for supporting and pivoting such armature in operative relation to such electromagnet, such spring adapted to normally hold such clapper mid- 55 way between such gongs and adapted to be flexed when such armature is acted upon by such electromagnet, means for maintaining the center of oscillation of such armature in the same position relatively to such electromagnet during the energization thereof, and means for subjecting such spring to initial tension during such energization while under conditions of rest such spring is free from tension.

60 In testimony whereof I affix my signature in presence of two witnesses.

WILLIAM W. DEAN.
